UNITED STATES PATENT OFFICE.

CHARLES A. BACON, OF LOCKFORD, CALIFORNIA, ASSIGNOR OF ONE-HALF
TO SAMUEL H. COHN, OF STOCKTON, CALIFORNIA.

ACETYLENE-GAS GENERATOR.

SPECIFICATION forming part of Letters Patent No. 653,373, dated July 10, 1900.

Application filed January 31, 1900. Serial No. 3,411. (No model.)

To all whom it may concern:

Be it known that I, CHARLES A. BACON, a citizen of the United States, residing at Lockford, county of San Joaquin, State of California, have invented an Improvement in Acetylene-Gas Machines; and I hereby declare the following to be a full, clear, and exact description of the same.

My invention relates to an apparatus which is designed for the economical production of acetylene gas from carbid of calcium.

It comprises a generator with a succession of independent carbid-containing boxes; a water-tank with a rising and falling gasometer and connections between this and the generator whereby the gas is transferred from the generator to the gasometer, with means for automatically cutting off the flow when the gasometer is sufficiently full; a means for automatically supplying water to the generator and a controlling-cock, actuated by the rising gasometer, whereby the supply of water is cut off when the gasometer is sufficiently full of gas; a trap intermediate between the water-supply and the generator, and a supplemental passage connecting with said trap and leading into the gasometer, whereby gas produced after the closing of the above-named valves is admitted into the gasometer and pressure upon the generator is relieved.

The invention also comprises details of construction, with means whereby two or more generators may be connected with a single gasometer and thrown into operation successively.

Referring to the accompanying drawings for a more complete explanation of my invention, Figure 1 is an elevation of the machine, partially in section. Fig. 2 is an elevation showing a generator upon each side of the tank. Fig. 3 is a sectional detail of the surplus-pipe and connections. Fig. 4 is a section through one of the baskets. Fig. 5 is a perspective view of the carbid-basket framework.

The gasometer-tank A may be of any suitable form and size adapted to contain water, and 2 is an open-bottomed gasometer adapted to rise and fall within the tank as the supply of gas is admitted or withdrawn therefrom.

3 is the generator, of which there may be

one or more, fixed with relation to the gasometer and having suitable connections whereby gas from the generator is delivered into the gasometer. The generator-case 3 has a suitably-packed cap or cover 4, with means by which it may be removed for the introduction of the carbid-containing boxes and hermetically closed while the apparatus is at work.

5 is a framework adapted to contain the carbid boxes or baskets 6. This framework, as here shown, consists of vertical bars or rods connected together transversely at the bottom and forming short legs at this point, which rest upon the bottom of the containing-chamber 3. The upper part of the framework is connected by a band 7, to which the upper ends of the vertical bars 5 are connected. These bars are here shown as arranged around half of the circumference of the carbid-containers, two of the bars forming sides and a third one the rear, against which the carbid-containers 6 contact when they are in place, the front or opposite side being open, so that they can be easily removed. A handle or bail 8 serves to easily lift the device out and replace it at will. In large machines the containers may be moved independently and the frame 5 be dispensed with. The carbid containers or boxes are cylindrical in shape and are of such size that each one will contain a certain charge of the carbid from which the gas is to be made. Around the upper periphery of the container 6 is a stiffening ring or wire forming a bead 6', adapted to keep the cover 9 away from the sides of the container to form a space for access to the holes hereinafter mentioned, said cover fitting upon each of the containers, forming a closure for the top. These containers have short legs or projections at the bottom, which serve to support them when superposed and leave sufficient space between them for the escape of the gas produced in the lower ones. At the same time the separation of the carbid into the chambers prevents the undue heating of the masses separated from those from which the gas is being actually produced. The surrounding water also assists to keep all parts cool. The tops of the covers 9 have holes punched from the interior upwardly, through which the gas can readily escape, and

small holes 10 are formed around the sides, close up to the rim of the containers, through which water can enter when supplied to the holder 3. The discharge-openings in the top 5 of the covers 9 being raised a little above the top of the cover, as shown at 11, prevent the water of condensation, of which a considerable amount is formed, from running into the carbid-holders before it is desired to moisten 10 the carbid. These holders being filled with the carbid and as many of them placed in the holding-frame 5 as required or desired, the frame is set into the case 3 and the cover closed and sealed.

15 12 is a water-supply pipe extending into the lower part of the tank A, and from this pipe a bent trap-pipe 13 extends upwardly transversely across the apparatus, then downwardly, and finally connects with the lower 20 part of the holder 3. This construction especially relates to the device as shown in Fig. 1, in which a single carbid-receptacle 3 is employed. The upward bend of the trap 13 is sufficient to prevent a pressure of gas from 25 the gasometer from forcing its way back through this water-supply. The water being admitted into the generator will rise until the lower container 6 is sufficiently submerged so that the water will enter through the holes 10 30 and, moistening the carbid, the generated gas will flow out through the holes 11 and rising within the case 3 will pass out through the pipe 14, which delivers it, as shown, into the interior of the gasometer 2, which will be 35 raised by the inflow of gas.

16 15 is a discharge-pipe, the upper end of which extends above the surface of the water within the gasometer-tank, and this pipe extends out through the side at the bottom and 40 connects with any desired service-pipes. When the gas production of the carbid from one of the chambers 6 has ceased, the water will rise and submerge the next one, and so on successively until all of the carbid-containers are successively exhausted. The ash 45 remaining is easily washed out by removing the top of the chamber 3, lifting out the framework 5, with its baskets, and when desired another set of freshly-charged baskets can be 50 inserted, the frame returned, and the work go on.

17 16 is a cock or valve in the gas-supply pipe 14, having a lever-arm 17 extending to one side. This arm has a fork, as shown at 18, 55 the construction of this lever being the same as lever 22 shown at the left-hand side of the tank in Fig. 1, said arm 17 being shown in edge view in said figure. 19 is a pin fixed to the vertical rod 20, which is carried by the 60 gasometer-tank 2 and extends down beside the forked lever, so that the pin 19 extends between the forks of the lever. These parts are adjustable to suit requirements. The upper fork of this lever is curved backwardly and 65 is shorter than the lower one, and this allows the pin 19 to be withdrawn from the fork as the gasometer rises; but this withdrawal only

takes place when the gasometer is as full of gas as may be desired, and at the instant of the withdrawal of the pin by the further rising 70 of the gasometer the cock through which the gas flows into the gasometer will be closed. No further supply can be received until the gasometer again sinks. When it does thus sink, the pin 19 will pass the upper arm of the 75 forked lever and will contact with the lower arm, thus pushing the lever down and again opening the cock to allow gas to enter the gasometer. The water-supply pipe or trap 13 has a similar cock 21, with a forked arm 80 22, which is operated by a pin 23 on the rod 24, carried by the gasometer, and said arm carrying a weight *w*, which acts through the arm to close off the water-supply to the carbid-containers when the gasometer has been 85 sufficiently filled with gas. When the gasometer rises to a certain height, the gas-inlet and water-outlet pipes are closed. The supply being cut off in an arm of the trap 13, no more water will flow from the tank A to the 90 carbid-holders; but the amount of water which is already in the generator will continue to produce a small amount of gas, which must be provided for. I have therefore shown a pipe 25, connecting with the upper 95 part of the trap 13, extending downward and entering into the bottom of the tank A. Above the pipe 25 extends a small valve-controlled pipe 25', which allows air to escape when the trap is first filled with water, and above the 100 pipe 15 is a pipe or guide 15' to guide the gasometer and prevent its turning. Within the tank this pipe rises and connects with a covered box or case 26, which is situated in the upper part of the tank and which has openings on 105 the top, these openings serving as an overflow. Any pressure of gas which continues to be generated after the main gas-admission valve has been closed will act through the trap 13, forcing any remaining water from the trap 110 and through the pipe 25 and up into the box 26, and if the supply is greater than this box will hold it will overflow gently into the tank A and without splashing or danger of throwing the water into the gas-pipes. Whenever 115 by use of the gas the gasometer again sinks, the main water and gas controlling valves will be opened and water will be again admitted to the gas-generator. The apparatus thus works automatically. As the gas produced in this manner is loaded with moisture, 120 I have shown a device consisting of carbid-containing chambers 27, with which the service-pipe connects, so that the gas from the service-pipe will flow through this dry carbid 125 before passing out for use. Above the containers 27 is a seal-cap 28, into which the gas passes. Thence it passes down through a passage at 29 and finally discharges into the service-pipe comparatively dry from its passage 130 through this body of carbid, which may be changed from time to time by removing the cap 28. 36 is a removable ash-receiver below these drying-chambers.

The apparatus, as shown in Fig. 2, has two generators suitably disposed with relation to the gasometer and its tank. In this case I have shown the water-supply pipe connected with each of the generators at the bottom, and they may be provided with cocks 30 to cut off the supply to either when recharging. At other times both cocks are open and water will pass into the generator which is delivering gas; but gas-pressure from the other keeps the water out until its gas-discharge cock has been opened after the first generator is exhausted. While one of the generators is in operation the gas passes therefrom through the transverse pipe 31, which connects the two generators and which is provided with cocks 32, operated by levers 33 and 34. Intermediate between these levers the pipe 31 connects with the pipe 14, which conducts the gas into the gasometer, and the lever 33 being in position to open the cock which it controls the gas will flow from pipe 31 through the open cock, and thus into the gasometer, as long as the generator with which it connects is producing gas. When this becomes exhausted, the gasometer will sink until a pin 38 on rod 39 will act to open the cock connecting with the right-hand generator, so that when this commences to produce gas the gas will flow through this cock and into the pipe 12, which connects with the gasometer. When the generators are both charged, one of the cocks is open and the other is closed, and when both generators are exhausted both cocks are left open. The trap shown at 13 in this case is arranged similarly to that previously described, so that any surplus pressure of gas after the cock between the generator and the gasometer has been closed will pass upward through this trap, thence down into the pipe 25, leading into the gasometer, as before described. This pipe may open into a box similar to 26, previously described, or, as here shown, it is inclosed in a larger perforated tube 37, so that any gas entering through this pipe will pass outward through the perforations in the tube in very fine streams and will thus not unduly agitate the water in the gasometer-tank.

By discharge-cocks 40 the generators may be washed out without opening the top. When this is done, air is admitted through cocks 41 to the water-supply pipes or traps to prevent the water from being drawn out of these parts by suction.

Where two generators are employed, as in Fig. 2, the water-supply pipe 12 connects with the bottom of the pipe 25, entering the gasometer-tank, and there are openings 43 at the bottom of this pipe interior to the tank to admit water to the pipe 25, while the pipe continues up within the gasometer and is inclosed in a perforated tube 37, as previously described.

Having thus described my invention, what I claim as new, and desire to secure by Letters Patent, is—

1. In an acetylene-gas machine, the combination of a generator, a gasometer and means connecting it with the generator, a frame consisting of vertical bars, a support near the bottom and a band at the top said frame having supporting-legs and being open at one side to permit the carbid-containers to be inserted and removed sidewise, the independent carbid-containers superposed one above another, means for admitting water into the generator at a point below the lowermost carbid-container, and means whereby the water successively enters each container after the carbid in the one below has become exhausted. 80

2. In an acetylene-gas machine, the combination of a generator, a gasometer and means connecting it with the generator, means for admitting water to the generator, carbid-containers including boxes having lugs at the bottom for separating adjacent boxes and thereby forming a gas-passage, said boxes formed with an annular bead at the top and a series of water-inlet passages below the bead, and covers for the boxes having depending flanges 90 covering the said inlet-openings and separated therefrom by said bead, and said covers having openings in their tops for the escape of gas into the space between the separated boxes. 95

3. In an acetylene-gas machine, the combination of a gasometer, a generator and a valve-controlled pipe connecting it with the gasometer, a valve-controlled water-supply pipe connecting the lower part of the tank with the generator, and having a vertically-disposed curved trap in its length, carbid-containers within the generator, and a pipe connection between the interior of the gasometer and the trap whereby gas which continues to generate when the valves are closed will act to force any remaining water from the generator into the gasometer, said connection also serving to transfer gas thus produced to said gasometer. 110

4. In an acetylene-gas machine, the combination of a gasometer, a generator, a valve-controlled pipe between the gasometer and generator, a valve-controlled water-supply, carbid-containers, and means connecting with the water-pipe whereby gas and water remaining in the generator after the main valves are closed are conducted to the gasometer. 115

5. In an acetylene-gas machine, a gasometer, a water-tank within which it is adapted to rise and fall, an exterior generator comprising a series of independent superposed carbid-containers, a pipe connecting the lower part of the gasometer-tank with the lower 125 part of the generator whereby water is admitted to successively submerge the carbid-containers, a pipe connecting the generator-chamber with the gasometer through which gas is delivered into the gasometer, a cock 130 and a lever-arm connected with and actuated by the rise and fall of the gasometer whereby:

4 said cock is closed when the gasometer is sufficiently filled, a similarly-actuated cock by which the water-supply to the generator is cut off at the same time, an upwardly-curved trap between the water-supply cock and the generator, and connections between the upper part of said trap and the interior of the gasometer whereby gas which continues to generate will act to force any remaining water from the generator into the gasometer, said connection serving also to transfer gas thus produced to the gasometer.

5 6. In an acetylene-gas machine, a gasometer, a tank containing water in which a gasometer is adapted to rise and fall, an exterior generator consisting of a vertical chamber, removable independent carbid-containers, superposed one upon the other within the generator, with openings whereby water may 15 be admitted and gas discharged from each container as they are successively submerged, a pipe connecting the upper part of the generator with the gasometer to deliver gas therein, a water-supply pipe connecting the lower 20 part of the gasometer-tank with the lower part of the generator, an intermediate upwardly-curved trap and connection between said trap and the interior of the gasometer, a cock whereby the direct admission of gas 25 from the generator to the gasometer is cut off when the latter is sufficiently filled, another cock by which the water-supply from the gasometer-tank is cut off from the trap at the same time, a connection between the trap and 30 the interior of the gasometer whereby the gas which is subsequently produced in the generator forces the remaining water back into the gasometer-tank, and an overflow box or device within the gasometer through which 35 the water and gas thus entering must pass.

7. In an acetylene-gas machine, a rising and falling gasometer, a water-containing tank within which the gasometer moves, a generator with independent carbid-containers, 40 means for supplying water to successively submerge said containers, a pipe connecting the upper part of the generator with the interior of the gasometer, a water-supply pipe connecting the lower part of the gasometer- 45 tank with the lower part of the generator and a trap intermediate thereof, a cock between the generator and the gasometer, and a similar cock between the water-tank and the trap leading to the generator, said cocks having 50 forked lever-arms connected therewith, the lower fork of each arm extending in line with the lever and the upper one forming a segmental curve of less length than the lower arm, rods connected with the gasometer ex- 55 tending vertically downward by the sides of said lever-arms and having pins fixed thereto and projecting so as to enter the forks of the levers, said pins acting to close the cock when the gasometer is sufficiently filled and to be 60 disengaged from the forked levers as they rise after said closing, and to again engage 65

the levers and open the cocks when the gasometer sinks.

8. In an acetylene-gas machine, a generator, a rising and falling gasometer, connections 70 between the generator and the gasometer for the transmission of gas and a controlling-cock therefor, other connections between the lower part of the gasometer-tank and the lower part of the generator for the transmission of water, 75 and a controlling-cock therefor, a trap intermediate between said cock and the generator, connections between said trap and the interior of the gasometer whereby surplus gas produced after the closing of the main cocks 80 is admitted into the gasometer, and water from the generator is also forced back, and an overflow box or device through which the gas and water thus transmitted are returned without agitation of the water in the gasome- 85 ter-tank.

9. In an acetylene-gas apparatus, a generator, a gasometer, connections by which the gas is transmitted from the generator to the gasometer, and a separate passage through 90 which surplus gas and water remaining in the generator after the main flow is cut off are also conducted to the generator, a pipe by which the gas is conveyed from the gasometer to the service-pipes, and a means for drying the gas 95 thus discharged, consisting of a dry-carbid container through which the gas is passed.

10. In an acetylene-gas machine, a gasometer, a water-containing tank in which it is adapted to rise and fall, a plurality of generators exterior thereto consisting of exterior chambers with removable hermetically-closed tops, a series of carbid-containers superposed and fitting each of the chambers, connections between the lower part of the gasometer-tank 100 and the lower part of the generators, and controlling-cocks whereby water is admitted successively to each of the generators, gas-conducting pipes opening from the upper part of the generators and connecting with a pipe 105 common to both which leads to the gasometer, cocks by which the branch to either generator may be closed or opened with connected lever-arms, rods connected with the gasometer having pins fixed thereto and adapted 110 to contact with the lever-arms whereby the latter are opened or closed by the movements of the gasometer, supplemental pipes leading from the branches of each generator, a trap 115 through which said pipes deliver into the 120 lower part of the gasometer whereby surplus gas generated after the closing of the main cock is allowed to pass into the gasometer, and a muffler or disperser whereby the flow of gas into the gasometer is prevented from 125 agitating the water in the gasometer-tank.

In witness whereof I have hereunto set my hand.

CHAS. A. BACON.
